SHOPPING BAG

Goble W. Bryant, Newburgh, N.Y., assignor to Interstate Bag Company, Inc., Walden, N.Y., a corporation of Virginia

Filed Dec. 31, 1963, Ser. No. 77,987

Term of patent 14 years

(Cl. D58—2)

The bands of ornamentation shown in FIGURE 1 are continuous as indicated by the broken lines.

The ornamentation has been omitted from the end panel in FIGURE 1 for convenience of illustration.

I claim:

The ornamental design for a shopping bag, as shown and described.
